UNITED STATES PATENT OFFICE.

SAMUEL GROSSMAN, OF NEW YORK, N. Y., ASSIGNOR TO KEL KLEBANOFF AND GROSSMAN, OF NEW YORK, N. Y., A COPARTNERSHIP CONSISTING OF DAVID KLEBANOFF AND SAMUEL GROSSMAN.

DESIGN FOR A FINGER RING.

Application filed April 15, 1927. Serial No. 21,610. Term of patent 3½ years.

To all whom it may concern:

Be it known that I, SAMUEL GROSSMAN, a citizen of the United States of America, residing at city of New York, county of Bronx, and State of New York, have invented a new, original, and ornamental Design for Finger Rings, of which the following is a specification, reference being had to the accompanying drawings, forming part thereof.

Fig. 1 is a side elevation thereof; Fig. 2 is a top plan view of a ring embodying the new design; and Fig. 3 is an edge view thereof.

I claim:

The ornamental design for a finger ring as shown.

In witness whereof I have signed this specification this 14th day of April, 1927.

SAMUEL GROSSMAN.
